(57) **CLAIM**

The ornamental design for a precision cutting tool, as shown and described.

DESCRIPTION

FIG. 1 is an isometric top, right, front view of a precision cutting tool;

FIG. 2 is an isometric bottom, left, rear view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.
